STRIKING CLOCK

Helmut Junghans, Schramberg-Sulgen, and Paul Jahn,
Schramberg, Germany

Application June 4, 1951, Serial No. 229,672.

Claims priority, application Germany June 5, 1950

5 Claims. (Cl. 116—169)

The present invention relates to striking clocks. In 15 striking clocks, the striking elements, for example, the gong rods usually employed, have been arranged on a wall, usually the rear wall, of the clock case, said wall serving as a resonance base. This arrangement makes it necessary to take into account acoustic requirements, 20 which take effect in the shaping of the clock case and in the selection and working of the material. In this case, it can be a disadvantage that the sharp inherent resonance of the resonant elements hitherto employed distorts the tone reproduction.

The object of the present invention is to provide sound radiating means for a striking clock which render possible an undistorted and thoroughly undamped radiation of the inherent vibration of the sound element, but which at the same time, from the point of view of cheapening and simplifying the construction and manufacture of the clock case, are substantially independent of its shaping and material composition. The invention aims at providing an assembly consisting of sound element and sound reflector which is adapted for use as an independent structural unit for a plurality of different housing shapes without special adaptation.

The solution of the object of the invention consists essentially in that a sound-reflecting diaphragm is associated with the sound element, the latter having a mechanical connection with the former. The diaphragm may cover an opening in a wall of the striker clock case, for example, in a side wall, but may be in any wall, or the top or bottom of the case. The reflection of sound by a diaphragm renders it possible for the striking clock case to be made of any suitable material, for example, of synthetic wood, and even of acoustically inert material. There is advantageously employed a rigid diaphragm, more especially a cone-shaped diaphragm, such as known in connection with loud-speakers. The base of the cone diaphragm can be made rectangular to correspond to the wall of the clock case in order to make full use of the space which is available; however, the corners at the base of the diaphragm will be rounded off in accordance with known acoustic requirements. On the other hand, however, it is also possible to employ a small diaphragm in conjunction with a sound horn to be built into the striker clock casing.

For increasing the quality and intensity of the sound, it is possible to interpose, between the sound element and the diaphragm, means for increasing the amplitude, for example, a lever transmission.

In striker clocks having a tubular gong as the sound element, the gong block is preferably suspended in a resilient manner from the clock case and with at least two degrees of freedom. The suspension may be effected by means of springs, but also in journals or knife-edge bearings, at least one half of the bearing consisting of a non-metallic material; finally, rubber bearings are also possible. As particularly advantageous for the purpose of an intensive and long-sounding pure tone-reproduction, the following arrangement may be used: The diaphragm

2

striker extends transversely, advantageously perpendicularly, or in the case of a coiled rod gong, normally and if desired in displaced parallel relation thereto, with respect to the place on the gong rod which is struck by the gong hammer, and more expeditely in the direction of the hammer blow. The transmission of the gong vibrations to the diaphragm is effected, in the preferred embodiment of the invention, via the gong block, a lever arm having an end connected with the diaphragm rod being rigidly secured to said gong block for increasing the amplitude of the diaphragm. In addition, with the preferred embodiment of the invention, using a gong with straight gong rods, the gong block is suspended by means of a wire spring bent to loop shape on a fixing angle plate in such manner as to be oscillatable about an axis perpendicular to the gong rods, or an axis displaced parallel to the perpendicular, and on said plate and on the gong block, there are provided means for holding the gong block when the clock is being transported.

Further features and advantages of the invention will be apparent from the following description of one constructional example, from the drawing and the claims.

In the drawings,

Fig. 1 shows a front elevation of a gong arrangement with diaphragm in a wall clock,

Fig. 2 is the arrangement according to Fig. 1, seen from the side.

1 is the rear wall and 2 is a side wall of a clock case, the remainder of which is not shown for the purpose of clarity. Secured to the rear wall 1, which may consist of any suitable material and even of acoustically inert material, is an angle plate 3 acting as support for a gong block 4. The gong block is suspended so as to vibrate resiliently by means of a wire spring 5 which is wound in a double loop and which, at a point 5a where the two loops run together, is connected, by a rivet 6, with the securing angle plate 3, and at its ends 5b, is connected by means of screws 7 to the gong block 4. Gong rods 8 are clamped in the gong block in known manner.

The striking hammer is indicated at 9 (Fig. 2), each of said gong rods 8 having a hammer associated therewith. The hammer shaft is represented at 10. The clock mechanism with the lifting arrangement for the hammers is not illustrated, since it can be of any generally known construction. The arrow 11 (Fig. 2) indicates the striking direction of the hammers. There is, of course, a hammer and its shaft for each gong rod.

The sound reflection is effected via a cone diaphragm 12, which is secured by the edge 12a of the base thereof over the wall opening 2a in the clock case wall. 12 is a rigid conical diaphragm which is known in connection with loud-speakers and made of compressed paper fibre or the like. By means of its point 12b, the diaphragm 12 is connected via a diaphragm rod 13 with an arm 4a of the gong block 4. The purpose of the arm 4a is to increase the amplitude of the diaphragm vibration.

It essentially adds to the reflection of the gong tones being effected with purity of tone and intensity in the embodiment illustrated if the diaphragm rod 13 is disposed perpendicular to the plane of the gong rods, and in the direction (11) of the striking of the hammers.

In order to prevent the diaphragm and the gong block suspension suffering damage during transport of the clock, the following securing arrangement is provided: Arranged on the fixing plate 3 is a raised portion 3a having a hole 3b, through which it is possible to insert a screw 14 (Fig. 1) and screw it into a threaded bore 4b in the gong block 4 until the latter, by yielding of its resilient suspension, is drawn rigidly against the raised portion.

Instead of using a gong with straight rods, as in the example illustrated, it would also be possible to provide

round bars or other sound elements, for example, bells, in conjunction with a sound-reflecting diaphragm. The use of the invention is not restricted to wall clocks with rectangular cases; it can also be employed with table clocks.

We claim:

1. Sounding mechanism for striking clocks comprising a gong block carrying gong rods, a striking member for each gong rod, a lever arm rigidly secured to said gong block, a cone-shaped diaphragm, a rod connected to a top of the cone of the diaphragm and to the said lever arm, spring means for resiliently supporting the gong block with respect to the wall of the casing of a clock, said spring means being shaped to allow vibrations of the gong block in the direction of the stroke of the striking member and additionally vibrations in a second direction.

2. Sounding mechanism for striking clocks comprising a gong block carrying gong rods, a striking member for each gong rod, a lever arm rigidly secured to said gong block, a cone-shaped diaphragm, a rod connected to a top of the cone of the diaphragm and to the said lever arm, spring means for resiliently supporting the gong block with respect to the wall of the casing of a clock, said spring means being shaped to allow vibrations of the gong block in the direction of the stroke of the striking member and additionally vibrations in a direction perpendicular thereto and to the gong rods.

3. Sounding mechanism for striking clocks according to claim 1, in which an angle plate is provided secured to

a clock and in which the spring means comprises a pair of wire springs bent to loop form and secured to the angle plate and the gong block to suspend the block from the angle plate.

5. Sounding mechanism for striking clocks according to claim 1, in which an angle plate is provided secured to a clock and in which the spring means comprises a pair of wire springs bent to loop form and secured to the angle plate and the gong block to suspend the block from the angle plate, each wire spring forming a single loop in spiral configuration.

10 15 5. Sounding mechanism for striking clocks according to claim 1, in which a case is provided having an opening in a wall thereof and the diaphragm is mounted adjacent the wall to cover the opening in the case.
